PHOTOELECTRIC ANNOUNCER OR SIMILAR ARTICLE

William G. Kahl, Jr., Brookfield, Conn., assignor to Arrowhead Enterprises, Inc., Bethel, Conn., a corporation of Connecticut

Filed Jan. 22, 1969, Ser. No. 15,448

Term of patent 14 years

Int. Cl. D13—99

U.S. Cl. D26—1

Fig. 2

Fig. 1

Fig. 4

Fig. 3

Fig. 6

Fig. 5

FIG. 1 is a perspective view of a photoelectric announcer or similar article embodying my new design; FIG. 2 is a top plan view thereof;

FIG. 3 is a front elevational view thereof;

FIG. 4 is a left side elevational view thereof, the right side elevational view being a mirror image;

FIG. 5 is a bottom plan view thereof; and

FIG. 6 is a rear elevational view thereof.

The bracket support is shown in broken lines in FIGS. 1-6 for illustrative purposes only.

I claim:

The ornamental design for a photoelectric announcer or similar article, substantially as shown and described.
